AIR DISTRIBUTION DUCT ASSEMBLY

Paul G. La Vigne, La Habra, Calif., assignor to Owens-Corning Fiberglas Corporation, Toledo, Ohio, a corporation of Delaware

Filed June 20, 1961, Ser. No. 118,331

3 Claims. (Cl. 98—33)

This invention relates to air distribution duct assemblies of the type usually employed with dropped or false ceilings and which serve to deliver and distribute centrally heated or cooled air to enclosures such as offices, etc. within a building and, frequently, to carry return air back to a central heating or air-conditioning apparatus.

This application is a continuation of my earlier pending application, Serial No. 123,601 filed February 28, 1961.

The invention consists in an air distribution duct assembly having elements which function for confining the air being distributed, for delivering it to different portions of the enclosure, for diffusing the air as it is delivered, and having ceiling-element-supporting means, and for cooperating, for example, with curtain walls for returning air.

The principal object of the instant invention is to provide a duct assembly having a main spine-like structural element and a duct cooperating therewith, the spine-like element being generally channel-shaped, and functioning to support and retain the duct in place, as well as to deliver air from the duct into the space, such as a room or other enclosure, in question.

It is another object of the instant invention to provide an elongated air-distributing channel adapted to be supported from overhead structural elements at a ceiling level and adapted to support ceiling elements and to communicate with the interior of the enclosed, elongated distribution duct throughout the length of the channel, for diffused delivery of air into the area beneath the ceiling.

It is yet another object of the instant invention to provide a duct for an air distribution system comprising a sheet of heat insulation material or the like so designed as to enable it to be shipped as a flat sheet and be readily folded into an elongated duct adapted for rapid assembly with an air distribution channel at the dropped ceiling level of a room or other enclosure, the duct being held and supported by the channel in the usual plenum that is formed above the dropped ceiling.

It is yet another object of the instant invention to provide an air duct assembly comprising two main structural elements, viz., an elongated air distribution channel and an elongated enclosed air distribution duct, the two elements being assembled for mounting at the ceiling level, either as an air supply duct assembly extending across a generally central portion of a ceiling, or as an air return duct assembly mounted at the top of a curtain wall, there being return air passages leading through the wall to its upper surface and into the duct assembly mounted atop the curtain wall.

It is a more specific object of the instant invention to provide a unitary air distribution channel suitable for fabrication as a metal extrusion and having suitable portions with legs, webs and flanges extending therefrom at suitable positions and attitudes for cooperation with ceiling elements, the side walls of ducts, diffusers, hanger means, ceiling support assembly means, cap structures for curtain wall, etc., in order to readily assemble these elements according to modern, dropped-ceiling, curtain-wall, building constructions.

These and other objects and advantages of a duct as-

2

sembly embodying the invention and of its elements will be better understood by reference to the following specification and to the attached drawings in which:

FIG. 1 is a fragmentary, vertical, and partly schematic sectional view through a room showing a dropped-ceiling and curtain-wall construction, and illustrating the employment of two duct assemblies embodying the invention, one as an air distribution duct assembly, and the other as an air return duct assembly in cooperation with a curtain wall having a return air passage.

FIG. 2 is a transverse vertical sectional view through a duct assembly embodying the invention and shown on an enlarged scale.

FIG. 3 is a fragmentary, perspective view of a duct constituting a part of the instant invention, the same being shown in its original flat form as manufactured and before being folded to form an elongated enclosed duct.

FIG. 4 is a cross-sectional view taken along the line 20 4—4 of FIG. 3 and shown on an enlarged scale.

FIG. 5 is a fragmentary view in perspective of the portions of two duct sections such as shown in FIG. 3 and folded to form enclosed, elongated duct sections, the same being shown assembled in longitudinal abutting relationship, one with the other, by means of a joint cover, and also showing portions of the air-distributing channel which constitute a part of the assembly of the instant invention.

FIG. 6 is a perspective view of a hanger for supporting a duct assembly embodying the invention from overhead support means.

In many modern buildings, such as those fabricated from structural steel and having reinforced concrete floors, the occupied spaces within the building are 35 bounded by dropped ceilings and so-called curtain walls. This manner of construction provides for a space, often two or three feet high and extending through the building just beneath each floor, called a plenum, with individual rooms on the floor separated from each other 40 by curtain walls which extend from the floor upwardly to the dropped ceiling. The plenum thus provided over the dropped ceiling and across the tops of the curtain walls is usually employed for the distribution of service elements and components, such as electrical cables, heating and air conditioning distribution systems, telephone 45 cables, etc.

FIG. 1 illustrates such a building construction, wherein there is shown an upper floor generally indicated at 10, and the next lower floor fragmentarily indicated at 11.

Attached to the underside of the upper floor 10 there is usually located a gridwork of overhead structural elements, for example, longitudinal support beams 12 and transversely extending support beams 13. A dropped ceiling in such a construction is often supported by a gridwork of inverted T-bars 14 and 15 which often are suspended from the overhead support structure by wires 16, or similar means. Adjacent spaces on the lower floor 11 are separated from each other by curtain walls or partitions, of which one is generally indicated by the 60 reference number 17.

The curtain wall 17 usually is based on a suitable base channel 18 and capped by a suitable cap or inverted channel 19, the wall 17 frequently being fabricated from sound-insulating material and, as in the case of the instant invention, having a plurality of return air passages 20. Each of the return air passages 20 communicates with its particular enclosed space through a suitable grill 21.

Air-distributing duct assemblies, according to the invention, are generally indicated in FIG. 1 by the reference numbers 22 and 22a, one of such assemblies (22) being

disposed at the center portion of the enclosure under consideration, and the other of such assemblies, indicated specifically by the reference number 22a, being shown atop the curtain wall 17. The air distribution duct assembly 22 is illustrated in FIG. 1 as functioning as a supply duct and the assembly 22a as a return duct.

Referring more particularly to FIG. 2, which shows a duct assembly 22, each of the duct assemblies 22 and 22a comprises an elongated air distributing U-shaped channel generally indicated at 23 and inverted to have an open bottom 24. Said channel 23 has two downwardly extending spaced legs 25 which, in the embodiment illustrated in the drawings, have inwardly offset upper continuations 25a that are connected by a transverse web 25b at the upper end of the channel. The air distribution channel 23 also comprises a pair of oppositely and outwardly directed flanges 29. Reference is here made to Patent No. 2,937,589, issued May 24, 1960, in which is disclosed an air outlet member or bar that embodies the above-described spaced legs, inwardly offset legs, transverse web, and outwardly directed flanges.

The channel 23 also comprises two laterally spaced pairs of parallel spaced webs 26 and 27 which extend upwardly from the channel legs 25, 25a to a level below the web 25b. In the embodiment of the invention shown in the drawings, the two pairs of webs 26 and 27 are outwardly as well as upwardly inclined and are located one on each side of a space 28 defined by the legs 25, 25a.

The flanges 29 function to support ceiling elements, such as the T-bars 15, or, more directly, a ceiling panel such as the ceiling panel 30 shown in the drawings, or lighting fixtures 30a, or other elements. At the outer sides of the legs 25, 25a and near their lower ends, each of them is formed with a pair of opposed slots 31 and 32 for the retention of the flat arm of a bent clip 33, the clip 33 having a return-bent end 34 which is hooked, for example, in an aperture 35 near the end of one of the T-bars 15 in order to retain the T-bar 15 in perpendicular abutment against the flange 29 of the channel 23 to provide two perpendicular ledges formed by the flange 29 and the cross bar of the T-bar 15 for holding perpendicular edges of a ceiling panel 30 or a fixture 30a.

In the embodiment of the invention illustrated in the drawings and following the teachings of Patent No. 2,937,589, the uppermost part 36 of the inverted channel 23 extends upwardly beyond the pairs of parallel webs 26 and 27 and a plurality of apertures 37 are drilled or punched in the leg extensions 25a near their tops. The channel part 36 has a T-slot 38 for the reception of heads 39 of a series of downwardly extending damper-adjustment screws 40 which are threaded through an inverted U-shaped damper 41. The lower end of each of the screws 40 is slotted so that a workman can insert a tool upwardly through the space 28 to rotate the screw 40 for adjusting the position of the damper 41 across and to partially close the apertures 37 for adjusting the flow of air therethrough.

The air distribution channel 23 supports and cooperates with a duct generally indicated by the reference number 42, which, in the embodiment shown, is triangular in shape, having a flat horizontal top 43 and two downwardly and inwardly converging side walls 44. The duct 42 is fabricated from a flat rectangular sheet 45 (FIGS. 3 and 4), of, for example, a compressed, fibrous insulating material such as glass fiber wool. The sheet 45 has parallel edges 46 and 47 and one face of the sheet 45 (lower face, FIGS. 3 and 4) is cut with two parallel V-shaped kerfs 48 and 49. The kerfs 48 and 49 are equidistantly spaced from the respective nearer edges of the sheet 45, i.e., the apex of the kerf 48 is the same distance from the edge 46 as is the apex of the kerf 49 from the edge 47. The kerfs 48 and 49 are cut at least substantially through the sheet 45 and their sides meet at an angle equal to the difference between 180° and the included angle between the top 43 and side 44 (FIG. 2).

of the duct 42 when the sheet 45 is folded to form the duct 42. The central portion of the sheet 45 between the kerfs 48 and 49 forms the top 43 of the duct 42, and the sides or outer portions of the sheet 45 form the side walls 44 of the duct 42.

The sheet 45 is backed up by an imperforate casing sheet 50 which serves two functions. First, the sheet 50, preferably formed from a light-gauge metal such as aluminum, provides structural integrity for the kerfed sheet 45 so as to retain the two side portions 44 and the central portion 43 of the sheet 45 as an entity; and second, the sheet 50 functions as a vapor barrier and encloses the duct 42 in its formed position (FIG. 2). The sheet 50 is adhesively secured to the upper face of the sheet 45, i.e., the outer face of the duct 42, by a suitable adhesive generally indicated at 51, by which the casing sheet 50 is laminated to the fibrous sheet 45 preferably before the kerfs 48 and 49 are cut. The casing sheet 50 has a pair of elongated, upwardly protruding loop hinges 52 formed by bending the metal of the casing sheet 50 prior to assembly with the fibrous sheet 45, which hinges 52 are aligned with and extend outwardly from the apexes of the kerfs 48 and 49. The side edges of the casing sheet 50 are turned up, forming elongated lips 53, and the casing sheet 50 is longitudinally staggered relative to the fibrous sheet 45 so that the casing sheet 50 extends beyond the fibrous sheet 45 at one end (indicated by the reference number 54) and the fibrous sheet 45 extends beyond the casing sheet 50 at the opposite end (indicated by the reference number 55). When two sections of duct 42 are assembled in end-to-end relationship, the overlapping end 54 of one of the casing sheets 50 overlaps the exposed end 55 of the next adjacent fibrous sheet 45.

The duct 42 is formed by bending the sides 44 of the fibrous sheet 45 downwardly toward each other, bending the loop hinges 52 of the casing sheet 50, until edges 56 of the sides 44 and edges 57 of the center portion 43 (duct top 43) are in mutual contact upon the closing of the kerfs 48 and 49. The duct 42 then has an inverted isosceles-triangular cross section with its top 43 extending generally horizontally and its sides 44 converging downwardly. The outer edges 46 and 47 of the fibrous sheet 45 are bevelled so as to accurately abut the outer sides of the leg extension 25a (FIG. 2) and the upper surface of a horizontal web 58 of the pairs of parallel webs 26 and 27.

After the duct 42 is folded into the isosceles-triangle configuration, the lower ends of the sides 44 are inserted downwardly between the pairs of webs 26 and 27 with the end of one of the sides 44 nesting between one of the pairs of webs 26 and 27 and abutting the web 58 and the lower end of the other of the sides 44 similarly nesting between the other pair of webs 26 and 27. As the lower ends of the sides 44 are inserted into place between their respective pairs of webs 26 and 27, the lips 53 at the sides of the casing sheet 50 are snapped beneath the down-turned rims 59 on the inner sides of the upper ends of the outer webs 26. This engagement of the lips 53 with the rims 59 functions to retain the duct 42 connected to the channel 23 and also to seal the space between the inner sides of the webs 26 and the portions of the outer sides of the duct sides 44 which extend downwardly into the spaces between the webs 26 and 27. This sealing is considered important because the casing sheet 50 not only has its first function of giving structural integrity to the duct 42 before folding, but also has its second function of serving as a vapor barrier and a heat reflector to prevent the passage of vapor into or out of the duct 42 and to reduce the heat transfer between either cold air or hot air interiorly of the duct 42 and the surrounding area of the plenum above the dropped ceiling.

Longitudinally adjacent sections of ducts 42 are assembled in end-to-end relationship, as described above and as illustrated in FIG. 5, where an exposed end 55

of a fibrous sheet 45 is shown and the engagement of the casing sheet 50 with the rim 59 of one of the webs 26 is also illustrated. The joint between longitudinally abutting duct sections is overlapped, as explained, and also is covered by a formed metal cover 60 having a top 61, two loop hinges 62, and downwardly extending arms 63 which closely embrace the corresponding elements of the casing sheet 50, and at their ends are similarly turned over to provide hooks (not shown) for engaging beneath the rims 59 and 59a of adjacent webs 26 and 26a of the two longitudinally abutting channels 23.

A duct assembly 22 according to the invention is suspended from the overhead structural elements 12 and 13 by means of support hooks 64 (FIG. 1), each of which is adjustably connected at the center of a cross channel 65 of a triangular hanger 66 (FIG. 6). The triangular hanger 66 also has two downwardly converging legs 67, each of which terminates in an inwardly turned hook 68 that is engageable beneath a downwardly turned flange 69 formed on the outer side of the outer web 26 of each pair of webs 26 and 27. The hanger thus supports the air distribution channel 23 which, in turn, supports its cooperating duct 42 and ceiling elements such as the ceiling panel 30 or the T-bar 15.

The open bottom 24 of the space 28 defined by the legs 25, 25a of the channel 23 has an air diffuser 70 which, in the embodiment shown, is a perforated trough fabricated from resilient sheet material and having turned-up edges which snap over downwardly extending ribs 71 located at the outer margins of the flanges 29 of the channel 23.

When an air distribution duct assembly of the invention is employed as a return duct, for example, the duct assembly 22a shown in FIG. 1, it is identical with that previously described, except that it does not employ a diffuser 70 and is assembled with a partition cap 19. The partition cap 19 is a channel having downwardly extending arms 72 embracing the upper edges of the partition or curtain wall 17, and a central portion 73 which protrudes upwardly into the space 28 between the legs 25 of the inverted U-shaped channel 23. A series of apertures 74 is formed in the central portion 73 of the cap 19 to provide for the flow of air upwardly out of the return air passage 26 into the space 28, through that space and through the apertures 39 in the upper part of the channel 23, and into the interior of duct 42a of the duct assembly 22a.

Air flows from the source through main floor ducts (not shown) to the air distribution duct assembly 22 of the invention, through the apertures 37 and the interior space 28 of the channel 23, and outwardly through the diffuser 70, into the interior of the space under consideration. Air flow arrows are shown in FIG. 1. Return air flows through the grill 21 and return air passages 26 in the curtain wall, through the apertures 74 in the cap 19 into the interior space 28 of channel 23a of the return air duct assembly 22a, and thence to main return ducts for the floor and to the air-treating apparatus.

Having thus described the invention, what is claimed and desired to be secured by Letters Patent is:

1. An air distribution duct assembly for use in an enclosed space having a main ceiling and comprising, in combination, (1) an elongated air distributing channel member, said channel member comprising a lower portion comprising a pair of laterally spaced, downwardly extending legs, and an outwardly directed, substantially horizontal sub-ceiling element support flange on the lower end of each of said legs, said legs defining therebetween a downwardly open air flow space, and an upper portion comprising a web extending upwardly from the upper portion of each of said legs and a generally horizontal cross element connecting said legs and webs in spaced parallel relationship, (2) a hollow, elongated, triangular air supply duct, said duct consisting of an inner layer of fibrous heat insu-

lating material and an outer, thin, sheet metal jacket for said insulating material and having a generally horizontal top and two downwardly converging sides and means at the corners of the top and the sides of said jacket for connecting said top and said sides, the lower ends of said sides of said duct extending downwardly between said upwardly extending webs on said channel member, there being air flow passageways through said upper portion of said channel member for communication between the air flow space defined by said legs of said channel member and the interior of said duct, means on said channel member for spacing the lower ends of said sides of said duct from each other and on opposite sides of said air flow passageways through said upper portion, (3) an elongated air flow diffuser at the open bottom of said air flow space between said legs of said channel member and (4) hanger means for supporting said duct assembly from said main ceiling.

2. An air flow system in combination with a room having a regular ceiling and a dropped ceiling forming a plenum chamber therebetween and a curtain wall extending from the room floor to said dropped ceiling comprising a pair of elongated hollow-duct assemblies, means for supporting one of said duct assemblies at the ceiling level of said dropped ceiling in the plenum above said dropped ceiling and in communication along its length with the room space beneath said dropped ceiling, said wall having at least one return air passage therethrough communicating with said room space and opening through the upper end of said wall, means for supporting the other of said duct assemblies in said plenum and atop said curtain wall with its interior in communication with the air passage in said curtain wall, said duct assemblies each comprising an elongated air-distributing inverted U-shaped channel having a bottom-open lower portion that is wider than the upper portion of the channel, two laterally spaced pairs of spaced parallel webs extending angularly upwardly from intermediate portions of the legs of said channel and terminating below the upper closed end of the channel, an outwardly extending ceiling-element-supporting flange at the lower end of each leg of said channel, a hollow, elongated polygonal duct having downwardly extending sides, the lower end of one of said sides extending below the closed upper end of the channel between the webs of one pair thereof and the lower end of the other of said sides extending below the closed upper end of the channel between the webs of the other pair, a thin imperforate casing enclosing said duct and extending downwardly within and below the upper edges of the outer webs of each pair of webs, the legs of said channel having air passages connecting the space defined between said legs to the interior of the duct, an air diffuser removably disposed below the open bottom of the channel of the first of said duct assemblies, and a perforated cap mounted on the top of said curtain wall and extending into the open bottom of the channel of the second of said duct assemblies.

3. A duct for an air distribution system, said duct being fabricated from a flat, rectangular sheet of compressed fibrous insulating material having parallel edges, one face of said sheet having two parallel V-kerfs cut therein, the kerfs being equidistantly spaced from the respective nearer edge of said sheet, the central portion of said sheet between the kerfs serving as a top for said duct and the outer portions outside the kerfs serving as sides for said duct, the kerfs extending at least substantially through said sheet and the sides of the kerfs meeting at an angle equal to the difference between 180° and the included angle between the top and the side of said duct when the sides thereof are swung downwardly for closing the kerfs, and a thin vapor-proof casing sheet adhered to the opposite face of said fibrous sheet, said casing sheet having an elongated, upwardly protruding loop hinge aligned with and extending outwardly from

the apex of each of the kerfs in said fibrous sheet, said duct being formed into a hollow elongated shape by folding said sides downwardly toward each other with the sides of said fibrous sheet converging, and the edges of said central portion and said side portions of said fibrous sheet originally defining the kerfs being in mutual contact.
